Application May 3, 1945, Serial No. 591,645

4 Claims. (Cl. 177—353)

1

This invention relates to a structurally and functionally improved controller and in its more specific aspects aims to provide a circuit-controlling mechanism useful in numerous different associations such as in the governing of a control mechanism and sign generally disclosed in United States patents to Unkles et al. 2,343,594 of March 7, 1944 and 2,422,149 of June 10, 1947.

In certain aspects, it is a primary object of the invention to furnish a controller which will present alternative structures and different functional characteristics over the forms of controller disclosed in the prior United States application to Bert W. Roth, filed in the Patent Office on July 27, 1944, and identified under Serial Number 546,884 now Patent 2,437,790, granted March 16, 1948.

A further object is that of providing a controller in which the actuating or code bars or their equivalents are operated in a positive manner such that circuits controlled by these bars will be efficiently opened and closed.

A still further object is that of furnishing a device of this type and in which the code bars or equivalent structures may be instantaneously shifted to desired positions and in response to the closing of certain controlling circuits.

Moreover, when so shifted—and in accordance with the present teachings—the parts will preferably remain in the desired positions for a sufficient interval of time to adequately accomplish the functions attributable to them; thereafter returning to inoperative, or positions at which they are potentialized for further operations.

An additional object is that of designing a controller in which frictional losses are reduced to a minimum. Thus, the operation of the controller may be relatively fast, the parts of the same will not tend to be distorted or become unduly worn, and, moreover, but minimum power will be required to secure efficient operation of the apparatus.

Another object is that of furnishing an apparatus of this type which will include relatively few parts, each individually simple and rugged in construction, these parts being capable of manufacture according to quantity production methods and being, moreover, capable of ready assemblage. When so assembled, a unitary structure will be furnished which will operate over long periods of time with freedom from all difficulties and which will, moreover, require a minimum of maintenance or servicing operations.

With these and other objects in mind, reference is had to the attached sheets of drawings

2 illustrating practical embodiments of the invention, and in which:

Fig. 1 is a perspective and somewhat "exploded" view of the essential portions of a mechanism with certain of its parts broken away to disclose underlying structures;

Fig. 2 is a fragmentary side view of certain of the parts as shown in Fig. 1;

Fig. 3 is a view similar to Fig. 1 but showing an alternative form of mechanism;

Fig. 4 is a diagrammatic side view of one of the relay elements as shown in Fig. 3; and

Fig. 5 is a fragmentary side view of a still further form of mechanism constructed in accordance with the present teachings.

It is preferred that the primary operation of a controller constructed in accordance with the present invention be secured by associating it with various forms of mechanism presently marketed by the Western Union and its subsidiary or affiliate corporations. Examples of these mechanisms are to be found in the United States patents to Kleinschmidt 1,448,750 of March 20, 1923 and Noxon et al. 2,252,232 of August 12, 1941. Apparatus such as is disclosed in those grants might generally be termed automatic typewriters or transcribing machines. They depend for their operation upon impulses of electrical current originating from a transmitter ordinarily operated by a tape formed with rows and permutations of perforations.

The details of the transmitter, perforated tape, the current path, etc., have not been illustrated in the present drawings. Suffice it to say that the structures which may be and are used in this connection are well known to those skilled in the art. Also, while the present invention has been shown and described in conjunction with a mechanism basically similar to an automatic typewriter or imprinting machine, it is apparent that a different power mechanism might be employed.

Thus, as shown in Fig. 1, the reference numeral 5 indicates a group of permutation bars formed with slots 6. These are moved laterally by means of suitable coils (not shown) or alternative assemblies in response to electrical impulses received by these assemblies or coils. Extending adjacent the permutation bars 5 are drop-in bars 7. The latter are biased towards the permutation bars by, for example, springs 8. Selector bars 9 may be coupled one to each of the drop-in bars 7. Where this apparatus has been heretofore employed as a typewriter, the selector bars have been coupled, either directly or indirectly, to

type-carrying bars which cooperated with a platen or other sheet-supporting surface upon which indicia was to be imprinted.

Preferably disposed immediately below the permutation bars 5 is a bail or rake member 10 which operates cyclically. When the rake extends outwardly as illustrated, it prevents any drop-in bar from moving into a groove or recess as defined by an aligned group of notches 6 in the several permutation bars. Under other conditions and when the rake or bail 10 has been shifted so as to not act as a stop or obstruction, one of the bars 7 has been free to move into notches 6 aligned in response to the shifting of the permutation bars 5. This will have the effect that that drop-in bar 7 has now been swung under the influence of spring 8 to a position at which the edge of the rake 10 will swing within its notch 11. Therefore, as the bail or rake moves upwardly, it will engage against the end edge of the notch and correspondingly move the drop-in bar 7 upwardly. This, in turn, will have the result that the selector bar 9 connected to the given bar 7 will likewise be swung. As the rake or bail 10 continues to operate, it will move the bar 7 out of the plane of the permutation bars 5. It may also assure that bar 7 returns to its normal position, in which the particular bar 7 will now engage the extended edge portions of one or more of the permutation bars, the notches 6 of which are no longer aligned with the particular bar 7.

For a full understanding of the operation of these portions of the mechanism, reference is had to the aforementioned Kleinschmidt and Noxon et al. disclosures. Suffice it to say that in accordance with the present teachings the parts of the standard mechanism beyond the selector bars 9 may be eliminated. In fact, except as a matter of convenience for mounting of the drop-in bars 7, the selector bars 9 might, themselves, be dispensed with. In this connection and as will hereinafter be more apparent, the switching mechanisms might be conveniently connected to any desired and proper part in order to assure their actuation.

However, there is retained as part of the standard assembly the shifting mechanism. This may include as shown levers 12 generally corresponding to the drop-in bars 7. These are operated in a manner similar to, or else identical with, the operation of these bars. Secured to the lower ends of each of the levers or bars 12 are cam members 13. Extending between the latter is a rod 14 which may mount adjacent its outer ends followers or contact portions 15 for engagement with the surfaces of the cams 13. The rod 14 is conveniently mounted by a block 16 slidably disposed between rails 17. Secured to the block is a stem 18. Beyond this, the more or less conventional mechanism is dispensed with and the structure of the present controller substituted.

One practical application of a controller constructed in accordance with the present teachings is—as afore brought out—to be found in associating the same with a sign control and system as generally disclosed in the afore identified Unkles et al. patents. The problem involved in such an installation would be that of having the proper elements or plungers of the setting head assembly disclosed in that patent, project or become operative in response to an actuation of a corresponding drop-in bar 7. Considering a drop-in bar 7 corresponding to the one which would normally cause the letter "A" to be imprinted, then it is desired substantially instantaneously

with the operation of that bar to have a permutation of setting head elements energized such that "A" will be reproduced. In other words, with such energization, the plungers of the heads will be projected so that they will intersect the paths of travel of corresponding switch elements of the rotor as disclosed in the Unkles et al. patent. Therefore, all switch elements necessary to provide the letter "A" on the illuminated sign will be simultaneously closed as the next adjacent row of switch elements passes the setting head station.

Accordingly, and as taught in the afore identified Roth application, a bank of switch elements corresponding in number to the number of setting head elements is provided. These switches are connected one to each of the setting head elements. The switches have, in the appended drawings, been indicated by the reference numeral 19. As illustrated, they each include a pair of arms insulated from each other and having normally spaced contacts. When one of the arms is shifted towards the other, a circuit through both arms is completed. As will readily be appreciated, these switches might take one of numerous different forms and might, in fact, form part of the actuating-shaft hereinafter described.

Similar to the disclosure of the Roth application, the bank of switch elements 19 is mounted upon a rotatable shaft 20. An actuating rod 21 may be secured to the switch assembly and connected to a lever 22 which is pivotally mounted as at 24. By means of a slot 23 formed in the lever 22, rod 21 may be operatively coupled thereto. The opposite end of the lever 22 is coupled by a pin and slot connection 25 with the extension or stem 18 secured to the block 16. It therefore follows as this block or its equivalent is shifted incident to an actuation of one or the other of the bars 21, the bank of switches mounted by the shaft 20 will be swung to occupy one of two extreme positions.

Actuating or code bars 26 are preferably disposed in a substantially vertical plane. Each of these bars, as in Fig. 2, carries projections or pins 27. The latter are on each bar arranged according to predetermined permutations such that corresponding switches in the bank 19 and in turn, for example, in the setting head of the sign control will be operated. Such operation will cause a desired letter, character or numeral to be established in the sign field conceding that the present controller is employed in such an association.

A coupling between these pins or projections of the bars 26 and the switch elements may be secured by suitably supporting for rotation two rows or banks of shafts 28. These shafts may terminate in heads 29, each carrying crank arms 30. Flaps or extensions 31 may, in any given pair of shafts, be disposed in opposed relationship. The adjacent edges of these flaps or extensions are spaced a distance slightly in excess of the width of bars 26. It therefore follows that the bank or row of bars 26 may be disposed in the space intervening the rows of flaps or extensions 31. As afore brought out, the cranks 30 may, if desired, form a part of the circuit-closing elements. Otherwise, and as shown, they may serve to actuate the individual switch elements. When shaft 20 is rocked to a forward position as illustrated in the drawing, the cranks 30 of the forward row of shafts 28 will cause operation of the switch elements. When shaft 20 has been operated to a point at which the longer arms of the switches overlie the cranks 30 of the rear

row, then the latter will operate the switch elements or directly close the circuits as their shafts 28 are oscillated. Under such circumstances, the forward row of shafts, while turning under the influence of forwardly extending pins or extensions 27, will not cause any direct actuation of the switch elements.

As will readily be appreciated, the power required to elevate the actuating or code bars 26 may, in certain instances, be relatively high. This will be especially true when quite a large number of switches are to be closed incident to a high number of projections or pins extending from any given bar. Also, if switches of the type shown at 19 are employed, it will be understood that the resistance to movement of these elements increases in direct proportion to the degree to which they have been shifted towards closed positions. In order to provide a simple and efficient structure, by means of which a positive shifting of the individual bars 26 will occur and such that each switch element will be properly closed, it is preferred that electro-magnets 32 may be employed.

Only three of these have been illustrated, but it will be appreciated that a number is employed which corresponds in number to the actuating bars 26. Ordinarily, in, for example, a machine such as is disclosed in the Unkles et al. patents, it will only be necessary to employ twenty-six code or actuating bars. Each of these, by permutations of pins or projections 27, will provide for a reproduction of one letter of the alphabet. Certain of the bars will have a dual function. In other words, there will be set up on their rear edges permutations of pins or projections 27 which will cover reference numerals 0 to 9 inclusive and two or three symbols. Thus, twenty-six bars and magnets will be adequate.

Each of the electro-magnets 32 will include a spring-projected armature 50. This armature is connected to an actuating element 33. The latter forms a part of a leverage system and may be in the nature of a wedge. Conveniently, the degree of projection of the armature may be limited by a stop 52. If desired, there may be embodied in the structure of the magnet a "hold-in" provision. In other words, when the circuit through the winding is closed, the armature will be immediately projected. Upon interruption of the circuit, the armature will remain in projected position for an interval of time. This interval will ordinarily not be in excess of $\frac{1}{10}$ of a second and in many installations may be as little as $\frac{1}{25}$ of a second. The actuating elements 33 cooperate with head portions 34 forming parts of the bars 26, and especially the inclined edges 35 thereof. These bars may be suitably guided and, in any event, should be anti-frictionally supported, for example, by rollers 53 at points adjacent the zone of the wedge elements 33. If the inclined faces of the wedges 33 and the cooperating inclined surfaces 35 each extend through angles of $22\frac{1}{2}^\circ$, it follows that a projection of one of the wedges 33 for a distance of, for example $\frac{1}{2}$ inch will raise a corresponding bar 26 a distance of $\frac{1}{4}$ inch. These distances may, of course, be varied and the angularity of the faces may likewise be varied.

As will be appreciated and with the magnets 70 deenergized, the wedge elements will slightly overlap the ends of edges 35. This will maintain the bars 26 in supported condition and so that they will not drop. With the leverage afforded by angles of $22\frac{1}{2}^\circ$, it is apparent that, in effect, 75

a two-to-one ratio is provided. Accordingly, the bars 26 are lifted in a positive manner and such that one may be assured the corresponding circuits will properly be closed. This structure also

- 5 has the advantage that by using electro-magnets in preference to other elements a unit is furnished which develops increasing power as the armature moves to attracted position. Such a result is to be desired in that during the initial 10 stages of elevating any given code bar relatively minor resistance may be encountered. As this resistance increases, the power with which the wedge element 33 moves also increases. Thus, no difficulties will be experienced in that connection.

In order to control the energization of the magnets, switches 36 are employed. These again correspond in number to the number of drop-in bars 7, the number of electro-magnets 32 and code bars 26. As illustrated, the magnets are preferably arranged in staggered relationship so that standard units may be employed without an undue crowding of the mechanism resulting. If the magnets are arranged in the form of two 25 rows, one above the other, then, for example, alternate bars 26 and particularly the head portions 34 thereof extend in two different planes. Similarly, the switches 36 are conveniently disposed in staggered relationship and the actuating 30 heads 37 of the bars 7 may extend in adjacent bars in opposite directions as shown in Fig. 1. Various other arrangements of the parts will readily suggest themselves and in order that the mechanism may be practically and efficiently 35 confined within a space of reasonable dimensions.

If it is found necessary to provide a mechanism to assure a retraction or return of the parts to their normal positions, this may be achieved in 40 a manner similar to that disclosed in the afore identified Roth application. Thus, a rod 38 may be movably mounted above the ends of the bank of bars 26. Normally, this rod is maintained in retracted position by spring-pressed bolts 39. 45 Cams or other suitable units cooperating with the upper surfaces of the heads 34 of the bars may serve—when actuated—to depress the latter against the action of the springs. When so depressed, the rod will contact the end of any head portion 34 of any code bar which does not, under the influence of gravity, tend to drop to its lowered or normal position. With the cams or their equivalents 40 actuated in properly timed 50 relationship and after all code bars are to assume their normal or depressed positions, it follows that any improperly elevated code bar will be depressed to that position. Likewise, there may be attached to the rod 38 a rod 41 which may extend into the spaces intervening the inward projections or flaps 31. This rod may carry the pins or projections 42 to engage one with each of the flaps or extensions. Therefore, any shaft 28 which has not, under the action of gravity or otherwise, returned to its normal position 55 will be shifted to that position as the rod 38 is depressed.

Under certain instances, difficulties might be experienced in assuring a positive retraction of the wedges 33. To overcome this, pins 43 may be secured, one to each of the wedges. These pins may be engaged by a sweeper bar 44 which is periodically swung rearwardly, or to the right, as viewed in the drawings. This bar, as well as the cams 40 or equivalent actuating mechanism

for the rod 38 may be actuated by electro-magnets.

All of the foregoing mechanisms may be modified in numerous particulars and certain of the same may be dispensed with if it is found unnecessary to employ them. Moreover, the structure of the several units may be changed in numerous respects and, if desired, the code or actuating bars 26 need not necessarily be disposed in a vertical plane. However, it is definitely preferred that these bars be actuated by a leverage system which conveniently has as its primary force an electro-magnet rather than to have some expedient such as that of pressing the bars 26 to circuit-closing positions by springs which are released by suitable mechanisms and then brought back to initial or potentialized condition by, for example, leverage or wedge systems. It is found in this connection that by having the code bars disposed in a substantially vertical plane gravity will ordinarily effect a return of the parts to normal position without the necessity of employing any supplemental springs or similar expedients.

Thus, as in Figs. 1 and 2 and with the parts set up in the manner afore described, it will be assumed that the permutation bars 5 are actuated so that in aggregate a single notch is presented. This may be entered by the drop-in bar aligned therewith. It will be appreciated that this operation will occur when the bail or rake is in a position permitting of this. Thereupon, the bail or rake member 10 will enter the notch 11 of the shifted drop-in bar 7 and elevate it. Assuming that the latter, rather than the selector bars 9, actuate the switches 36, it follows that the head portions 31 will shift the switch parts to close the circuits. With such closing, a corresponding electro-magnet 32 will be energized. As the drop-in bar 7 returns to its normal position, the corresponding switch 36 will be opened, thus interrupting the circuit. As afore brought out, if it is found that the electro-magnet 32 should remain energized for a period of time in excess of that during which the switch 36 is closed, then a "hold-in" provision embodied in the electro-magnet will provide the desired results.

With the energization of a particular magnet 32, the inclined surface 35 of the head 34 of a code bar which has heretofore been merely supported by a wedge element 33 extending from the magnet will have a camming effect transmitted to it. This will result in the code bar's being elevated to a desired extent and with sufficient force to assure closing of what might be termed all the secondary circuits through the switches 19. Also, these switches or their functional equivalents will remain closed for the entire period of time (as afore brought out) that the magnet remains, in effect, energized and its wedge element 33 remains projected.

As has been previously seen, the drop-in bars carry permutations of pins or projections 27 by means of which the desired switches are closed. This follows as a consequence of the projections or pins engaging the flaps or extensions 31 affixed to the shafts 28 and rotating these shafts so that the crank 30 will cooperate with the desired switches 19 to close circuits through them.

Whether such closing results in an energization of circuits such that, for example, a letter rather than a numeral or character is displayed will depend upon the position to which the block 16 has been shifted. Obviously, when one of the bars 12 is shifted as a consequence of the actua-

tion of the permutation bars, its cam portion 13 will cooperate with the rods 14 to move the block 16 and its extension 18 in one direction. When the other bar 12 is shifted, its cam portion will return the block 16 and connected parts to their original positions. Depending upon the position of the block 16, the assembly of switches 19 will be correspondingly shifted. Wherever one of the actuating bars 26 has a dual function, then, regardless of such shifting, a subsequent operation of the bar will cause a closing of selected switches of the bank or group 19.

Various other forms of mechanism for accomplishing the desired results may be constructed within the teachings of the present invention. As illustrative of one of these, attention is next directed to Figs. 3 and 4. In the first of these figures, a mechanism corresponding generally to that illustrated in Fig. 1 has been shown. However, in this form of mechanism, the lever 22, instead of shifting a bank or group of switches 19, serves to shift, for example, an element 54 of a switch assembly. Thus, this element may bridge the space between contacts 55 or 56. Conveniently, these contacts are connected to a common source of power supply 57. However, leads 58 and 59 extend from the different pairs of contacts and are coupled respectively to a series of relays 60 or a series of relays 61. The former are relays of the letter type whereas the latter are relays of the numeral or symbol type.

As illustrated especially in Fig. 4, each of these relays serve to operate a multiplicity of switch elements 62. From the latter, leads 63 extend to the units to be energized (for example, the elements of the setting head as disclosed in the aforementioned Unkles et al. patent). Leads 64, in addition to branches of leads 58 and 59 extend from each relay. These leads 64 are connected one to each of the switches 36 as previously described in connection with Fig. 1.

As will be apparent in this form of mechanism, the switches 36 will be closed or actuated as heretofore described. Depending upon the position of the "shift" mechanism, current flow will occur through either leads 58 or 59 to potentialize and operate either one of the series of relays 60 or one of the series of relays 61. Therefore, with the closing of a predetermined switch 36, a corresponding relay will function. This will result in a closing of the switch elements 62 controlled thereby in order to energize the several leads connected to the switches to thus operate the mechanisms coupled to these leads. Again, a disc or so-called button 65 may be associated with the relay and serve as a "hold-in" provision to assure that the switches 62 remain closed for a sufficient interval of time such that an adequate functioning of the mechanisms coupled therewith occurs.

Thus, depending upon the position of the switching mechanism 54, either the leads 58 or 59 will be energized to correspondingly potentialize either the series of relays 60 or 61 for operation. With the closing of any switch 36 connected to an individual relay that relay will accordingly act to close the group of switches 62. Thus, a mechanism is again furnished in which the force of movement of the drop-in bars 7 is greatly magnified when translated into a force which serves to operate the group of switches.

A similar result may be obtained by the mechanism shown somewhat diagrammatically in Fig. 5. In that view, the reference numeral 65 indicates an actuating bar corresponding to one of

the bars 26 as in Fig. 1. Again, a power-transcribing mechanism such as is shown in the former view is employed. Switches 36, individual to the drop-in bars 7, are utilized. These switches serve to control a flow of current through magnets 67. The latter correspond in number to the number of actuating bars 65. Bell-crank levers are pivotally coupled one to each of the actuating bars 65. Each of these levers comprises an arm 66 and an arm 66'. The latter serves to normally maintain the arm 66 in the position shown in full lines. The magnet 67 may cause a shifting of the bell-crank to the position indicated in dotted lines. In series with the magnet 67 is a relay 68. The latter may have a hold-in provision or button 70 and a delayed-action provision or button 69. An armature 71 in the form of a switch is actuated by the relay 68. When this switch is closed, lead 72 is energized to cause a flow of current through magnet 73. The latter is connected to operate a bell-crank lever 74. This may conveniently carry a rake or bail 75 which will have a path of movement beyond the arm 66 of any of the individual bell-crank levers except when the latter are in retracted positions.

Thus, in this structure, it is apparent that with the operation of any drop-in bar the corresponding switch 36 will be closed. This will assure an instantaneous energization of magnet 67 to swing the bell-crank lever 66-66' from the position indicated in full lines to that indicated in dotted lines. In such a position, the arm 66 will intersect the path of travel of the bail or rake 75. With the current flow continuing through the relay 68, the latter will be energized to close the switch 71. This will cause current to flow to the magnet 73.

However, the latter will not be energized to operate the rake 75 until an appreciable interval (for example $\frac{1}{10}$ to $\frac{1}{25}$ of a second) has elapsed after the closing of the switch 36. Therefore, the rake 75 will not shift until arm 66 has been attracted by magnet 67 to a position where it will be engaged by the rake or bail. It is for this reason that the delay provision or structure 69 is provided as part of the relay. Having in mind that switch 36 may very quickly open after it has once been closed and the fact that the actuating bar 65 should remain in elevated position for an appreciable interval of time, the reason for the hold-in provision or button 70 will be apparent.

More particularly, as the rake 75 swings upwardly, it will thrust against the arm 66 of the bell crank lever. This thrust will result in an elevation of the actuating bar 65. With, now, the relays 68 remaining energized (again for an interval of, for example, from $\frac{1}{10}$ to $\frac{1}{25}$ of a second) beyond the time that the switch 36 is opened, it will be apparent that the mechanism of the controller as shown in Figs. 1 and 3 may be potentialized for the operation of a further bar 7 and switch 36 without this interfering with the continued elevation of the bar 65. After the interval of time has elapsed, the bail will permit the actuating bar to lower and the bell-crank lever 66 will shift to its normal position.

As afore brought out, a number of actuating bars 65 are employed. The number conveniently may be twenty-six to correspond to the number of letters of the alphabet. A corresponding number of magnets 67 are utilized, one individual to each of the bars. The same is true of the lever assembly 66-66'. In view of the fact that the

relay 69 simply serves to energize and de-energize the magnet 73 or equivalent bail-operating unit, either a single relay 68 may be employed or else a number of the same may be provided. In the former instance, the leads from all of the magnets 67 will be coupled to that relay. In the latter instance, any desired number of relays (for example, twenty-six) may be utilized. The switches 71 of these relays are connected to energize the lead 72. Only a single magnet 73 or its equivalent is necessary.

Thus, it is apparent that among others the several objects of the invention as specifically afore noted are achieved. Obviously, numerous changes in construction and rearrangements of the parts might be resorted to without departing from the spirit of the invention as defined by the claims.

I claim:

20. 1. A controller including in combination a group of movably mounted, notched permutation bars, a group of drop-in bars movably mounted to be extendable into the notches of said permutation bars, means for shifting those drop-in bars which are so extended, a group of switches to be actuated by the shifting of said drop-in bars, power multiplying means connecting said latter bars with said switches whereby the shifting of any drop-in bar will produce sufficient power to operate the switches connected therewith, a lever movably mounted to be extendable into the notches of said permutation bars and means controlled by the movements of said lever for rendering certain of said switches inoperative to be actuated by the shifting of any predetermined drop-in bar.
25. 2. A controller including in combination a group of movably mounted, notched permutation bars, a group of drop-in bars movably mounted to be extendable into the notches of said permutation bars which are so extended, a group of switches to be actuated by the shifting of said drop-in bars, code bars movably mounted and connected with said switches to operate the latter and power multiplying means connecting said code bars with said drop-in bars whereby the movement of said code bars will produce sufficient power to operate the switches connected therewith.
30. 3. A controller including in combination a group of movably mounted, notched permutation bars, a group of drop-in bars movably mounted to be extendable into the notches of said permutation bars, means for shifting those drop-in bars which are so extended, a group of switches to be actuated by the shifting of said drop-in bars, code bars movably mounted and connected with said switches to operate the latter, electromagnets connected to said code bars to forcibly shift the latter and further switches individual to each of said electromagnets and operable in response to a shifting of the drop-in bars whereby the shifting of the latter will through said electromagnets and code bars transmit sufficient force to actuate said group of switches.
35. 4. A controller including in combination a group of movably mounted, notched permutation bars, a group of drop-in bars movably mounted to be extendable into the notches of said permutation bars which are so extended, a group of switches to be actuated by the shifting of said drop-in bars, code bars movably mounted and connected with said switches to operate the latter, electromagnets connected to said code bars to forcibly shift

the latter, further switches individual to each of said electro-magnets and operable in response to a shifting of the drop-in bars whereby the shifting of the latter will through said electro-magnets and code bars transmit sufficient force to actuate said group of switches and means for retarding the deenergization of said electro-magnets after any of the further switches connected therewith have been opened.
